(CL. D81—10)

To all whom it may concern:

Be it known that I, Arthur D. Altemiller, a citizen of the United States, residing at Affton, St. Louis County, State of Missouri, have invented a new, original, and ornamental Design for a Combination Popcorn Warming and Display Cabinet, of which the following is a specification, reference being had to the accompanying drawing, forming a part thereof.

Fig. 1 is a front perspective view of a combination warming and display cabinet embodying my new design; and

Fig. 2 is an elevational view of the left end not shown in Fig. 1.

The rear of the cabinet is substantially plain.

I claim:

The ornamental design for a combination popcorn warming and display cabinet, substantially as shown and described.

ARTHUR D. ALTEMILLER.
